SASH PULLEY BRAKE

William G. Smith, Tarentum, Pa., assignor to
Pittsburgh Plate Glass Company, Allegheny
County, Pa., a corporation of Pennsylvania

Application June 30, 1941, Serial No. 400,546

3 Claims. (Cl. 16—194)

The present invention relates to window constructions and more particularly to a sash pulley structure for use in conjunction with double-hung, vertically sliding windows.

One object of the invention is to provide a brake for a sash pulley in order to permit controlled movement of a window sash, the counterbalanced arrangement of which has been disturbed by the addition thereto of an auxiliary glazed sash.

Other objects and advantages of the invention will become more apparent from the following detailed description of a preferred embodiment thereof.

Modern adoption of air conditioning in the building field has occasioned the development of multiple plate window units to reduce heat transmission through the glazed areas of buildings. The application of auxiliary glazed frames to the ordinary window sash would appear to be a simple matter, but it results in a rather difficult problem aside from the question of installation. The additional weight of the auxiliary frame disturbs the counterbalanced arrangement of the sash and window weight. Accordingly it is not only more difficult to raise the insulated sash but also the sash will not stay in its elevated position. It is not possible to substitute a heavier counterbalancing weight because there is not sufficient room in the window frame.

Briefly stated, the present invention contemplates the addition of a braking device to the standard sash pulley in such manner that it will permit free rotation thereof in one direction but will automatically engage and retard rotation of the pulley in the opposite direction.

One form of the invention is shown in the accompanying drawing, wherein:

Figure 1 is a front elevational view of a double-hung vertically sliding window construction to which the invention is applicable.

Figure 2 is a fragmentary vertical sectional view, on an enlarged scale of the sash pulley structure showing the braking device in operative position.

Figure 3 is a side elevational view of the braking device; and

Figure 4 is an end elevational view of the braking device.

Referring to the drawing, a window structure 1 includes a frame 2 positioned in a wall 3, and sashes 4 connected by cords 6 passing over pulleys 7 to counterbalance weights 8. The weights 8 lie within the frame 2 and are approximately of a size to compensate for the weights of the sashes

to which they are attached. This portion of the structure is conventional to most forms of double-hung vertically sliding windows.

My invention is concerned primarily with a control device for the sash pulleys as shown in Figure 2. The pulleys 7 are secured upon horizontal axles 10 mounted within housings 11 of metal from which extend flanges 12, which are fastened to the frame 2 by means of screws 14. The control device 16 comprises a brake-shoe 17 substantially of crescent shape with an enlarged base portion which fits within a flanged guideway 19 secured to an angle bracket 20. A bolt 21 passes through the bracket and serves to maintain the shoe 17 within the guideway, which is slotted, as indicated at 22, to permit a lateral movement of the shoe 17. The bracket 20 is secured to the lower portion of the pulley housing 11 in such manner that the brake-shoe 17 engages the pulley 7. In this position the shoe 17 also contacts the cord 6 passing over the pulley 7.

When the sash 4, bearing the additional weight of an auxiliary frame, is in an elevated position the cord 6 on the inner side of the pulley will be under tension. This tension will force the brake-shoe 17 against the pulley 7 and prevent its rotation to lower the sash. The frictional engagement may, however, be overcome by the application of slight force to the sash and it may thus be lowered at will. Since the braking action is operative in one direction only, the sash may be raised in the normal manner. In raising the sash, the cord 6 is under tension on the outside of the frame due to the window weight suspended thereon, but the cord on the inside of the frame is fairly loose. Accordingly the brake is not forced against the pulley and rotation thereof is not impeded. In fact rotation of the pulley is accompanied by a movement of the brake-shoe away from the pulley. As soon as the weight of the sash is returned to the cord the brake-shoe is urged against the pulley and its rotation is halted.

The operation of the control device is entirely automatic. Its simplicity in construction and installation are also important factors favoring its adoption.

It will at once be apparent that various modifications in the nature and arrangement of the elements of my invention are possible without departing from the spirit thereof or the scope of the appended claims.

What I claim is:

1. In a window mounting including sash struc-

ture and a counterweight of less weight than the sash structure, a cable connected to the counterweight and to the sash structure, a pulley rotatable in the upper portion of the window mounting and having the cable trained thereover to support the sash structure on the cable in vertically movable relation whereby the sash structure tends to overbalance the counterweight, a support having a surface disposed in the mounting below the pulley in spaced relation to the latter, and a brake shoe wedgeably mounted between the support surface and the pulley, said support having means for guiding the shoe on the surface thereof, a portion of the brake shoe having an outer surface over which the cable is bulged for instituting the wedging action of the shoe between the support surface and pulley in response to movement of the cable over the pulley in one direction.

2. In a window mounting including sash structure and a counterweight of less weight than the sash structure, a cable connected to the counterweight and sash structure, a pulley rotatable in the upper portion of the window mounting and having a cable trained thereover to support the

sash structure on the cable in vertically movable relation whereby the sash structure tends to overbalance the counterweight, a brake shoe engageable with the lower portion of the pulley and having an extension disposed laterally of the pulley substantially along the surface thereof, said cable bearing against the shoe extension and normally pressing the latter against the pulley, and means carried by the mounting for movably supporting the shoe against the pulley.

3. A window sash brake construction for exerting one-way braking action upon a weighted cable-and-pulley unit comprising a brake support, and a shoe having a brake surface curved to correspond substantially to the curvature of the pulley and movable on said support into wedging and braking relation between the support and pulley, said support having means for guiding the shoe slidably thereon, said shoe having an outwardly projecting portion to bulge the cable outwardly adjacent the pulley and being responsive to the cable in one direction of movement of the latter to press the shoe into a wedging and braking relation to the pulley.

WILLIAM G. SMITH.
